UNITED STATES PATENT OFFICE.

JAROSLAV RICHTER AND RUDOLF JEŽEK, OF HOLICE, CZECHOSLOVAKIA.

DESIGN FOR A SOLE FOR A SHOE.

Application filed July 6, 1928, Serial No. 27,401, and in Czechoslovakia May 8, 1928. Term of patent 14 years.

To all whom it may concern:

Be it known that we, JAROSLAV RICHTER and RUDOLF JEŽEK, both citizens of Czechoslovakia, and both residing at Holice, in the county of Bohemia, Czechoslovakia, have invented a new, original, and ornamental design for a Sole for Shoes, of which the following is a specification, reference being had to the ac-

companying drawing, forming part thereof.

The figure is a perspective view of a sole for shoes showing our new design.

We claim:

The ornamental design for a sole for a shoe as shown.

JAROSLAV RICHTER.
RUDOLF JEŽEK.
